UNITED STATES PATENT OFFICE.

EDWIN W. WEBB AND CHARLES S. WALTON, OF CHICAGO, ILLINOIS, ASSIGNEES TO
STANDARD CAR TRUCK COMPANY, OF CHICAGO, ILLINOIS, A CORPORATION OF NEW
JERSEY.

CAR-TRUCK.

1,235,745.

Specification of Letters Patent. Patented Aug. 7, 1917.

Application filed August 12, 1916. Serial No. 114,556.

To all whom it may concern:

Be it known that we, EDWIN W. WEBB and CHARLES S. WALTON, citizens of the United States, residing at Chicago, in the county of Cook and State of Illinois, have invented certain new and useful Improvements in Car-Trucks; and we do hereby declare the following to be a full, clear, and exact description of the invention, such as will enable others skilled in the art to which it appertains to make and use the same.

Our invention relates to improvements in car trucks and particularly to six-wheeled equalized car trucks. To the above end, generally stated, the invention consists of the novel devices and combinations of devices hereinafter described and defined in the claims.

In the accompanying drawings, which illustrate the invention, like characters indicate like parts throughout the several views.

Referring to the drawings,

Figure 1 is a view principally in side elevation of the improved car truck with some parts shown in vertical section and other parts diagrammatically illustrated by means of broken lines;

Fig. 2 is a fragmentary plan view of the same;

Fig. 3 is a view principally in transverse vertical section taken on the line 3-3 of Fig. 1;

Fig. 4 is a view in vertical section taken on the line 4-4 of Fig. 1; with some parts removed; and

Fig. 5 is a detail view in section taken on the line 5-5 of Fig. 1, on an enlarged scale.

Each side frame of the improved car truck is indicated by the numeral 1 and, as shown, is of cast steel with a general cross section in the form of a box-like structure, the walls of which are suitably reinforced. In each end of the side frame 1, is a spring-pocket 2 formed in the top member thereof with its bottom located slightly thereabove. Formed in the under side of the side frame 1, are two intermediate and relatively large spring-pockets 3.

Two-part depending pedestals 4 are located between each pair of spring-pockets 2 and 3 and between the pair of spring-pockets 3. The upper sections of the pedestals 4

are cast integral with the side frame 1 and the lower sections thereof are detachably but rigidly secured to said upper sections by nut-equipped bolts 5. The lower extremities of each pair of pedestals 4 are rigidly connected by a tie bar 6. These tie bars 6 are detachably secured to the pedestals 4 by nut-equipped bolts 7 and the ends thereof are bent upward and engage the outer faces of the pedestals to prevent lateral separation thereof. Chafing plates 8 extend substantially the full length of the pedestals 4 and cover the joints between the sections thereof.

A bolster opening 9 is formed in the side frame 1 over each spring-seat 3 and the bottoms of said spring-seats form the bottoms of the bolster openings. Over each pair of pedestals 4, is formed in the side frame 1 a horizontally elongated opening 10, the purpose of which will presently appear.

The car truck wheels and their axles are indicated by the numeral 11 and the journal boxes therefor are indicated as entireties by the numeral 12, with the exception of rectangular bearing seats 13 formed in the tops thereof. The journal boxes 12 may be of any desired form, are mounted between the pedestals 4 and have, on their sides, the customary pedestal guides.

The side frames 1 are rigidly connected by two pairs of angle tie bars 14, having their horizontal flanges turned toward each other and the ends thereof rest on brackets 15 to which they are rigidly secured by rivets. These brackets 15 are cast integral with the walls of the spring-pockets 3 and project inward therefrom. The vertical flanges of each pair of tie bars 14 are turned upward and their horizontal flanges are edgewise spaced apart to permit the escape of dust and dirt therebetween.

The bolster for the improved car truck is of the double type of cast steel and, as shown, is made up of a center beam 16, outer beams 17 and tie eye-beams 18. The bolster beams 17 are located directly, one over each pair of tie bars 14 and their ends are inserted through the bolster openings 9 and have formed on their under faces roller contours 19, which rest on lateral motion rollers 20. These rollers 20, in turn, are mounted in roller contours 21 formed in roller bases 100 22 seated on the bottoms of the bolster open-

ings 9. On the sides of the bolster beams 17, are stop lugs 17^a arranged to engage the inner faces of the side frames 1 to limit the lateral movement of the bolster. The beams 5 17 are rigidly connected and held in parallel arrangement by the tie bars 18, the ends of which rest upon said beams 17 and are bolted thereto. The center beam 16 is supported by the tie beams 18 and its ends rest on the 10 lower horizontal flanges of said tie beams and are riveted to the webs thereof. A lower center bearing 23 is cast integral with the center beam 16.

While the bolster shown is made up of 15 several members rigidly connected by bolts and rivets, it is, of course, understood that the same may be cast as an entirety. Side bearing plates 24 are riveted to the tie beams 18 in line with the center beam 16 and prevent excessive rocking of the car.

Intermediately fulcrumed on each journal box 12, is an equalizing lever 25 having on its under side a fulcrum lug 26 mounted in the bearing seat 18 of the respective journal box 12. These equalizing levers 25 extend transversely of the journal boxes 12, are located within the side frames 1 and have in each of their ends an elongated vertically extended aperture 27. A yielding abutment 28 is interposed between the outer end of each outer equalizing lever 25 in the side frame 1. These abutments, as shown, are in the form of coiled springs 28 seated on spring-bases 29 and extend in the pockets 2. The spring-bases 29 have on their under sides diametrically opposite fulcrum lugs 30 seated in notches 31 formed in the upper edges of the respective fulcrum levers 25. These fulcrum lugs 30 support the 35 spring bases 29 above the equalizing levers 25 and thereby permit the required oscillatory movement of said levers. At the centers of the spring-bases 29, are depending lugs 32, which extend into the underlying 40 apertures 27 in the outer ends of the outer equalizing levers 25 and hold said base plates in position thereon.

Spring-seat bars 33 are horizontally suspended under the spring-seats 3 by flat 50 links 34 from the inner ends of the outer equalizing levers 25 and the ends of the inner equalizing levers 25. Fulcrum lugs 35, in the form of keys, are extended transversely through the links 34 at the ends thereof. The upper fulcrum lugs 35 are seated in notches 36, formed in the upper surfaces of the equalizing levers 25, and support the links therefrom and the lower fulcrum lugs 35 are seated in notches 37, formed in the under sides of the spring-seat bars 33, and support said spring-seat bars thereon. The links 34 are loosely extended through the apertures 27 to permit the required flexibility of the levers 25, 60 spring-seat bars 33 and links 34. Four

coiled springs 38 are seated on each spring-seat bar 33 and extend in the overlying spring-pocket 3.

Brake-hangers 39 are secured to the inner sides of the side frames 1 by rivets. By 70 reference to Fig. 4, it will be noted that the upper members of the pedestals 4 and the upper ends of the chafing plates 8 are notched or cut away to afford clearance for the equalizing levers 25. In assembling the 75 improved car truck, the openings 10 in the side frames 1 make it extremely simple and easy to position the outer equalizing levers 25 and the spring-abutments 28.

It will be noted that the pedestals 4, 80 equalizing levers 25, spring-seat bars 33 and links 34 are all of one pattern, respectively, making the construction simple and easy to replace parts, in case of wear or breakage.

From the above description, it is evident that the load of the car is directly on the double bolster and it, in turn, bears directly on the side frames through the lateral motion rollers. The weight on the side frames 90 is applied directly over the several groups of springs 38, which carry said side frames from the journal boxes through the equalizing levers, links and spring-seat bars. The spring-abutments 28 compensate for the 95 movement of the equalizing bars on the journal boxes. By the construction and arrangement of parts, just referred to, each wheel is allowed to move vertically, independent of the others thereof.

The compactness of the above described invention is such that an extra pair of wheels is added, without increasing the length of the truck over a four-wheeled truck, thereby increasing the capacity of 100 the truck with no additional weight placed on a given length of roadbed.

What we claim is:—

1. In a car truck, the combination with side frames, journal boxes and a bolster, of 110 equalizing levers intermediately fulcrumed on the journal boxes, abutments between the outer ends of the equalizing levers and side frames, spring seat bars carried by the inner ends of the equalizing levers, and 115 springs interposed between the spring seat bars and side frames at points under the bolster.

2. In a car truck, the combination with side frames and journal boxes, of equalizing levers intermediately fulcrumed on the journal boxes, abutments between the outer ends of the equalizing levers and side frames, spring seat bars carried by the inner ends of the equalizing levers, springs interposed 120 between the spring seat bars and side frames, and anti-friction bearing devices on the side frames over said spring.

3. In a car truck, the combination with side frames and journal boxes, of equaliz- 130

- ing levers intermediately fulcrumed on the journal boxes, spring-abutments directly supporting the side frames on the outer ends of the equalizing levers, spring-seat bars carried by the inner ends of the equalizing levers, and springs interposed between the spring-seat bars and side frames. 5
4. In a car truck, the combination with side frames and journal boxes, of equalizing levers intermediately fulcrumed on the journal boxes, spring-abutments directly supporting the side frames on the outer ends of the equalizing levers, spring-seat bars, links suspending the spring-seat bars from the inner ends of the equalizing levers, and springs interposed between the spring-seat bars and side frames. 10
5. In a car truck, the combination with side frames and journal boxes, of equalizing levers intermediately fulcrumed on the journal boxes, spring-abutments between the outer ends of the equalizing levers and side frames, spring-seat bars carried by the inner ends of the equalizing levers, springs interposed between the spring-seat bars and side frames, and anti-friction bearing devices on the side frames directly over said springs. 15
6. In a car truck, the combination with side frames and journal boxes, of equalizing levers intermediately fulcrumed on the journal boxes, spring-abutments between the outer ends of the equalizing levers and side frames, spring-seat bars carried by the inner ends of the equalizing levers, springs interposed between the spring-seat bars and side frames, lateral motion bearing devices on the side frames directly over the said springs, and a bolster carried by the lateral motion bearing devices. 20
7. In a car truck, the combination with side frames and journal boxes, of equalizing levers intermediately fulcrumed on the journal boxes, spring-abutments directly supporting the side frames on the outer ends of the equalizing levers, spring-seat bars, links extended through apertures in the inner ends of the equalizing levers and the ends of the spring-seat bars and pivotally connected to both thereof, and springs interposed between the spring-seat bars and side frames. 25
8. In a six-wheeled car truck, the combination with side frames, a double bolster and journal boxes, of equalizing levers intermediately fulcrumed on the journal boxes, abutments between the outer ends of the outer equalizing levers and side frames, and bars carried by the inner ends of the outer equalizing levers and the intermediate equalizing levers and supporting the side frames under the bolster. 30
9. In a six-wheeled car truck, the combination with side frames, journal boxes and a double bolster, of equalizing levers intermediately fulcrumed on the journal boxes, abutments between the outer ends of the outer
- outer equalizing levers and side frames, and bars carried by the inner ends of the outer equalizing levers and the intermediate equalizing levers and supporting the side frames directly under the double bolster. 70
10. In a six-wheeled car truck, the combination with side frames, journal boxes and a double bolster, of equalizing levers intermediately fulcrumed on the journal boxes, spring-abutments between the outer ends of the outer equalizing levers and side frames, and bars carried by the inner ends of the outer equalizing levers and the intermediate equalizing levers and supporting the side frames directly under the double bolster. 75
11. In a six-wheeled car truck, the combination with side frames and journal boxes, of equalizing levers intermediately fulcrumed on the journal boxes, spring-abutments directly supporting the side frames on the outer ends of the outer equalizing levers, spring-seat bars carried by the inner ends of the outer equalizing levers and the intermediate equalizing levers, and springs interposed between the spring-seat bars and side frames. 80
12. In a six-wheeled car truck, the combination with side frames and journal boxes, of equalizing levers intermediately fulcrumed on the journal boxes, spring-abutments directly supporting the side frames on the outer ends of the outer equalizing levers, spring-seat bars, links suspending the spring-seat bars from the inner ends of the outer equalizing levers and intermediate equalizing levers, and springs interposed between the spring-seat bars and the side frames. 85
13. In a six-wheeled car truck, the combination with side frames and journal boxes, of equalizing levers intermediately fulcrumed on the journal boxes, spring-abutments between the outer ends of the outer equalizing levers and the side frames, spring-seat bars, links suspending the spring-seat bars from the inner ends of the outer equalizing levers and intermediate equalizing levers, springs interposed between the spring-seat bars and the side frames, and anti-friction bearing devices on the side frames directly over said springs. 90
14. In a six-wheeled car truck, the combination with side frames and journal boxes, of equalizing levers intermediately fulcrumed on the journal boxes, spring-abutments between the outer ends of the outer equalizing levers and the side frames, spring-seat bars, links suspending the spring-seat bars from the inner ends of the outer equalizing levers and intermediate equalizing levers, springs interposed between the spring-seat bars and the side frames, lateral motion bearing devices on the side frames directly over said springs, and a bolster carried by the lateral motion bearing devices. 125

15. In a car truck, the combination with a cast side frame, the general cross section of which is in the form of a box, spring-pockets formed in the end and intermediate portions of the side frame, and depending pedestals between the end and intermediate spring-pockets.
16. In a car truck, the combination with a cast side frame, the general cross section of which is in the form of a box, spring-pockets formed in the end and intermediate portions of the side frame, a bolster opening above the intermediate spring-pocket, and depending pedestals between the end and intermediate spring-pockets.
17. In a six-wheeled truck, the combination with a cast side frame, the general cross section of which is in the form of a box, spring-pockets formed in the end and intermediate portions of the side frame, a bolster opening above each intermediate spring-pocket, and depending pedestals between the end and intermediate spring-pockets and between the two intermediate spring-pockets.

In testimony whereof we affix our signatures in presence of two witnesses.

EDWIN W. WEBB.
CHARLES S. WALTON.
